UNITED STATES PATENT OFFICE.

HENRY RUPPERT, OF CHICAGO, ILLINOIS.

CAR-COUPLING.

SPECIFICATION forming part of Letters Patent No. 452,067, dated May 12, 1891.

Application filed October 27, 1890. Serial No. 369,399. (No model.)

To all whom it may concern:

Be it known that I, HENRY RUPPERT, a citizen of the United States, and a resident of the city of Chicago, county of Cook, and State 5 of Illinois, have invented certain new and useful Improvements in Car-Couplers, of which the following is a specification.

This invention relates to improvements in that class of car-couplers in which the link is 10 held in position by a manually-operated support for guiding the link into the opposing draw-head in the act of coupling the cars together. In all such devices, of course, it is necessary that the immediate support for the link 15 should rise to a plane between the draw-head; and prior to this invention, so far as I am aware, all these devices have been dependent upon the alertness and promptness of the brakeman or other attendant to withdraw them 20 from between the draw-heads after the link has entered the opposing draw-head, in order to save them from being crushed and bent beyond usefulness between the draw-heads, which come together with considerable force 25 in coupling.

The prime object of this invention is to have a support for the link which will automatically move from between the draw-heads as they come together in coupling, whereby 30 all danger of injury to the support and its operating devices is avoided.

Another object is to have a knockdown or dropping support for the link, which will be struck by the opposing draw-head and drop 35 from between the draw-heads after the link is properly guided into the draw-head.

A further object is to have the link-support so operated that when released by the operator it will automatically resume its normal position for coupling without manual manipulation, whereby the operator is relieved of the danger and necessity of going between the cars at any time, either in the coupling operation or after the coupling is effected for re- 45 storing the support to the position for effecting another coupling.

These objects are attained by the devices illustrated in the accompanying drawings, in which—

50 Figure 1 represents a perspective view of the end of a car showing a coupler applied thereto embodying my invention; Fig. 2, a

side elevation showing the ends of opposing cars in the act of coupling.

Similar letters of reference indicate the 55 same parts in the several figures of the drawings.

Referring by letter to the accompanying drawings, A indicates the draw-head, and B the link carried thereby, both of the ordinary 60 and well-known construction of car-couplers usually employed upon freight-cars.

To the end of the car is pivotally secured by means of bearing-boxes C, a link-lifter D, formed of a bent-rod, gas-piping, or similar 65 material, the ends of which terminate in handles E, one at each side of the car, for manipulating the lifter, and the middle portion of which is bent outwardly from the bearing, so as to form a bail F extending around the 70 draw-head when elevated into position to support the link. The middle portion of this bail is bent at an angle to the main body thereof, and serves as a pivot for a drop or knockdown support G, which is the immediate 75 support of the link in the coupling operation, as illustrated in the drawings. This knockdown support is free to turn upon its pivot, and may be of any suitable construction and dimensions, but when raised to position for supporting the link it normally stands slightly off and forward of its pivotal center, being sustained in that position by stops H at each side thereof engaging the bail, but when struck by the opposing draw- 80 head in the act of coupling, the support will be forced back past the center and drop down out of the way upon a suitable rest I, also attached to and carried by the bail, as illustrated by the dotted line in Fig. 2.

In both figures of the drawings I have shown the link-lifter elevated and in position to support the link in the act of coupling; but the normal position of the lifter when uncontrolled by the hand of the operator is shown 95 by the dotted lines at the left of Fig. 2, the handle assuming a horizontal position parallel with the car-body, while the bail hangs vertically from the bearings of the lifter.

In practice the operator grasps one of the 100 handles of the lifter and draws it downward, thus elevating the bail until the link-support engages and lifts the link carried by the draw-head so as to guide it into the opposing draw-

head with which it is intended to couple. As soon as the link has fairly entered the opposing draw-head the link-support is struck and knocked down out of the way by the opposing draw-head, so that when the two draw-heads come together the link-support is out from between them and safe from injury. When the coupling is effected, the operator releases the handle and the bail swings down to its normal position, thus causing the knock-down support for the link to fall back by gravity off of the rest in position for again supporting the link, so that when it is desired to effect another coupling it is only necessary for the operator to manipulate the handle and the link-support will rise up in proper position.

With a device of this character cars of different heights may be as readily coupled as those of equal heights, and in all cases the support for the link will drop out from between the draw-heads safe from injury as soon as the link is fairly engaged by the opposing draw-head.

I do not desire to limit myself to the exact construction and arrangement of parts herein shown, for obviously the link-support may be of different form, construction, and dimensions, and the stop and rest therefor may be obtained in numerous other ways, but such

variations will be no departure from the spirit of my invention, which, broadly stated, is a knockdown support for the link, which will fall or recede from between the draw-heads when they come together, and which will automatically resume its normal position after each coupling.

Having described my invention, what I claim, and desire to secure by Letters Patent, is—

1. In a car-coupler, the combination, with the link-lifter, of the knockdown support for the link carried thereby, substantially as described.
2. In a car-coupler, the combination, with the link-lifter, of a knockdown support for the link pivotally secured thereto, and a stop and rest for said support, substantially as described.
3. In a car-coupler, the combination, with the link-lifter pivotally secured to the car-body, terminating at its ends in handles, and at its center formed into a bail, of the knockdown support for the link pivotally secured to said bail and a stop and rest therefor, substantially as described.

HENRY RUPPERT.
